E. PRESTAGE

HIGH PRESSURE GAS COMPRESSOR

Filed Jan. 7 1925

INVENTOR:
Edwin Prestage
BY: Francisco E. Beyer
ATTORNEY

UNITED STATES PATENT OFFICE.

EDWIN PRESTAGE, OF LONDON, ENGLAND, ASSIGNOR OF ONE-HALF TO H. J. WEST
AND COMPANY LIMITED, OF LONDON, ENGLAND.

HIGH-PRESSURE GAS COMPRESSOR.

Application filed January 7, 1925, Serial No. 956, and in Great Britain October 16, 1924.

This invention relates to an improvement in or modification of the high speed gas compressor described in United States Patent Specification No. 1,167,658 dated January 11th, 1926, as used for refrigerating purposes and has for its object the provision of means whereby varying evaporator pressures may be admitted to the compressor successively so that increased efficiency is obtained.

In connection with refrigerating apparatus it is ordinary practice to employ a compressor common to several requirements as for example, the manufacture of ice and storage of comestibles which are required to be maintained at a comparatively high temperature to that used for ice making or the storage of frozen meat, so that in the case of storage of some comestibles a higher evaporator pressure prevails as compared with that required for ice making or frozen meat storage, and according to this invention as hereinafter described by the admission of such higher evaporator pressure into the compressor at or near the end of its suction stroke the gas within the cylinder at the lower pressure is partially compressed preparatory to the compression stroke taking place.

The prevailing pressure of a fore-cooler when such is used in connection with the cooling of water preparatory to the manufacture of ice would equally well serve the purpose.

In order that my invention may be readily understood reference may now be had to the accompanying drawing in which is illustrated in sectional elevation so much of a compressor of the type to which reference has been made with my improvements applied thereto in which the cylinder 1 is provided with two annular chambers 2 and 2^a the former co-acting with ports or passages 6 in the sleeve valve 4 as described in Patent Specification No. 467 of 1914 whilst the latter co-acts with the ports or passages 6^a when the same are uncovered by the descent of the piston 7.

Presuming now that the compressor is employed for the dual purpose of making ice and the maintenance of a store at a suitable temperature for the preservation of eggs the evaporator pressure in the former instance will be very much lower than that in the latter, consequently if the suction

pipe from the ice making tank or evaporator is connected up to the belt or chamber 2 and the suction pipe from the storage chamber or evaporator in connection therewith to the belt or chamber 2^a it will be obvious that by the descent of the piston 7 and the downward movement of the sleeve valve 4 the cylinder will be first charged with gas at a comparatively low pressure and when the piston 7 has descended sufficiently and the sleeve valve 4 by its return upward movement having closed the ports 6, the ports or passages 6^a are brought into register with the belt or chamber 2^a by the upward movement of the sleeve valve 4 and the higher pressure prevailing in the storage evaporator coils will be admitted to the cylinder from the belt or annular chamber 2^a and compress the gas already therein preparatory to the effective upstroke of the compressor piston.

Obviously when a fore-cooler is employed in connection with the compressor the cold gas coming from the evaporator is more or less heated by the water used for ice making and consequently its pressure is thereby raised and this may be connected up to the belt or chamber 2^a and used for the purpose set forth.

Under certain circumstances a difference of evaporator pressures may not be available and in order to ensure the complete filling of the cylinder with gas from the evaporator I prefer to interconnect the two belts or chambers 2 and 2^a by the passage 8 which is opened or closed by the manipulation of the stop valve 9 associated therewith as shown.

The sleeve valve 4 is provided with piston rings 10 of any suitable construction and the false head may be fitted with a mushroom delivery valve 15 as shown but any other form of valve may be employed although as described in the aforesaid patent specification a delivery or discharge valve is not absolutely necessary.

What I claim is:

1. A high pressure compressor for ammonia or carbonic acid gas comprising a cylinder with two series of gas inlets spaced around its wall and communicating with two annular chambers surrounding the cylinder, a piston reciprocating in said cylinder, a sleeve valve reciprocating between the piston and the cylinder with two series

105

110

of ports adapted to register with said gas inlets successively so that firstly low pressure gas is admitted to the compressor cylinder during the downward travel of the piston and at the end of the stroke thereof a supplementary supply of high pressure gas is admitted to the cylinder for the purpose set forth.

2. A high pressure compressor for ammonia or carbonic acid gas comprising a cylinder with two series of gas inlets spaced around its wall and communicating with

two annular chambers surrounding the cylinder, a piston reciprocating in said cylinder, a sleeve valve reciprocating between the piston and the cylinder with two series of ports adapted to register with said gas inlets successively and means for interconnecting the two chambers adjacent to the cylinder.

In testimony whereof I affix my signature.

EDWIN PRESTAGE.

of ports adapted to register with said gas inlets successively so that firstly low pressure gas is admitted to the compressor cylinder during the downward travel of the piston 5 and at the end of the stroke thereof a supplementary supply of high pressure gas is admitted to the cylinder for the purpose set forth.

2. A high pressure compressor for ammonia or carbonic acid gas comprising a cylinder with two series of gas inlets spaced around its wall and communicating with

two annular chambers surrounding the cylinder, a piston reciprocating in said cylinder, a sleeve valve reciprocating between 15 the piston and the cylinder with two series of ports adapted to register with said gas inlets successively and means for interconnecting the two chambers adjacent to the cylinder. 20

In testimony whereof I affix my signature.

EDWIN PRESTAGE.

Certificate of Correction.

Patent No. 1,614,851.

EDWIN PRESTAGE.

Granted January 18, 1927, to

It is hereby certified that error appears in the printed specification of the above-numbered patent requiring correction as follows: Page 1, line 5, for the year "1926" read 1916; and that the said Letters Patent should be read with this correction therein that the same may conform to the record of the case in the Patent Office.

Signed and sealed this 29th day of March, A. D. 1927.

[SEAL.]

M. J. MOORE,
Acting Commissioner of Patents.

Certificate of Correction.

Patent No. 1,614,851.

Granted January 18, 1927, to
EDWIN PRESTAGE.

It is hereby certified that error appears in the printed specification of the above-numbered patent requiring correction as follows: Page 1, line 5, for the year "1926" read *1916*; and that the said Letters Patent should be read with this correction therein that the same may conform to the record of the case in the Patent Office.

Signed and sealed this 29th day of March, A. D. 1927.
